UNITED STATES PATENT OFFICE.

AUGUST J. EGGERSS, OF OMAHA, NEBRASKA, ASSIGNOR TO EGGERSS-O'FLYING COMPANY, OF OMAHA, NEBRASKA, A CORPORATION OF NEBRASKA.

SHIPPING CONTAINER FOR PLOWSHARES.

Application filed July 18, 1923. Serial No. 652,349.

To all whom it may concern:

Be it known that I, AUGUST J. EGGERSS, a citizen of the United States, residing at Omaha, in the county of Douglas and 5 State of Nebraska, have invented certain new and useful Improvements in Shipping Containers for Plowshares, of which the following is a specification.

My invention relates to shipping containers and packages, and it is the object thereof to provide a simple, efficient and inexpensive container for shipping plowshares. Because of their weight, irregular shape, and their sharp edges and points, 10 plowshares offer a special problem in preparing the same for shipment in such a manner as to avoid damage thereto; or to other articles thereby, without employing an expensive or heavy shipping container, 15 such as a wooden box or crate. The present commercial practice consists in wrapping the plowshare with burlap, which is sewed or tied to hold it in place about the article, extra thicknesses of the wrapping 20 material being disposed about the point and edges of the share. It is found that, owing to the pliability of the burlap, the portions of the wrapping about the point and edge of the plowshare are easily cut through 25 when such portions of the package are struck against or by any solid object, with the result that the point or edge is then 30 subject to damage, or the wrapping may be cut through to an extent permitting its entire loss, together with the shipping tag or 35 other means by which the origin and destination of the package may be determined. The above mentioned objections, arising from the use of a pliable fabric wrapping 40 for plowshares, are completely avoided by the use of a container made of relatively stiff or rigid material capable of maintaining a definite form independently of the object inclosed by it, the container being 45 shaped to conform with the major outlines of the plowshare in flat planes. My invention provides a container of this kind, which may be produced at a moderate cost, and which is of minimum weight.

50 In the accompanying drawings Fig. 1 is a plan view of a structure embodying my invention, the container being in the flat or extended form, Fig. 2 is a perspective view of the same in the closed or folded form, 55 Fig. 3 is a plan view of the closed container,

Fig. 4 is a side view of the same, and Fig. 5 is a transverse section on the line 5—5 of Fig. 3.

In the production of my container I preferably employ the material known commercially as double-faced corrugated strawboard, or, more briefly, as corrugated board, said material consisting of a sheet of corrugated strawboard having at each side thereof a facing of flat strawboard secured thereto by adhesive material. From said material, by means of suitable dies or cutters, I form a blank of substantially the form represented in Fig. 1, the blank being creased to facilitate bending thereof along the outlines of the several parts of the blank. The main or central portion 7 of the blank is trapeziform, its longitudinal edges 8 and 9 being slightly convergent toward the end 10, said end 10 being approximately perpendicular to the longitudinal edge 8, and the opposite end 11 being diagonal to form an acute angle with the edge 8 and an obtuse angle with the edge 9. From the longitudinal edge 8 is extended the flap 12, of which the shape is substantially symmetrical with the adjacent longitudinal half of the central part 7 of the blank. At the end 10 is a triangular or wedge-shaped wing 13 of which the acute-angled apex terminates at the edge 8, one of the longer sides of said portion 13 being homologous with the end 10 of the part 7, and the opposite side 14 having the quadrangular flap 15 extending therefrom. 80 From the longitudinal edge 9 of the part 7 there is extended the narrow quadrangular wing 16, and to the outer edge 17 of said wing there is joined the trapezoidal flap 18. From the diagonal end 11 of the 85 part 7 there is extended the triangular or wedge-shaped wing 19, of which the acute-angled apex adjoins the edge 8, one of the longer sides of said wing being homologous with the end 11, and the opposite side 20 being joined with the pentagonal flap 21. 90 The blank is creased along the lines 8, 9, 10, 11, 14, 17 and 20, and is bent substantially at right angles along all of said lines except 8 and 17, the bend of the latter being to an angle slightly less than a right angle, and the bend at the line 8 being to an acute angle complementary to the angle of the bend at 17.

100 Referring to Figs. 2, 3, 4 and 5, it will be 110

seen that the container formed by bending of the blank is triangular or wedge-shaped in transverse section, the part 7 forming the bottom, the wings 13 and 19 forming the ends, the wing 16 forming the side opposite the apex of the wedge, and the flaps 12 and 18 overlapping the flaps 15 and 21 to form the upper side of the container.

The relation of the plowshare to the container will be apparent from Figs. 1 and 5. The sole of the share A rests upon the bottom 7 of the container, so that the landside end B is adjacent to the end-portion 19, the point C of the share extending into the corner at the juncture of the fold-lines 8 and 11, the edge D of the share being adjacent to the fold-line 8, the heel E of the share adjoining the end-portion 13 of the container, and the upper or moldboard edge F of the share adjoining the side 16 of the container. The form of the container may be regarded as a pentahedral prism which closely approximates the major outlines of the plowshare, and which is capable of so confining the same as to prevent the sharp point C or edge D of the share

from cutting through the inclosure. Any tendency of the plowshare to move longitudinally of the container will result in the flat landside end B striking the end 19 of the container, or the flat heel E striking the end 13. Likewise, any tendency of the share to shift in the direction of the edge D is prevented by the confinement of the wide rear portion of the share between the bottom and top of the container, as will be obvious from Fig. 5.

Now, having described my invention, what I claim and desire to secure by Letters Patent is:

A shipping container for plowshares, comprising an integral sheet of corrugated board having a trapeziform central portion, a trapeziform flap at one of the longitudinal edges of said central portion, a quadrangular wing at the opposite longitudinal edge of the central portion, a trapeziform flap at the outer edge of said wing, triangular wings at each end of said central portion, and flaps at the outer edges of said triangular wings.

AUGUST J. EGGERSS.
